UNITED STATES PATENT OFFICE

2,431,198

BASE STRUCTURE FOR MINIATURE
ELECTRON TUBES

Sam Posen, Chicago, Ill., assignor to Beltone
Hearing Aid Co., Chicago, Ill., a corporation of
Illinois

Original application March 17, 1944, Serial No.
526,877. Divided and this application January
4, 1945, Serial No. 571,218

3 Claims. (Cl. 250—27.5)

1

This application is a division of my copending case Serial No. 526,877, filed March 17, 1944.

This invention relates to midget electron tubes and has for its main object to provide a midget electron tube which is particularly suited for the use in wearable hearing aids or similar small instruments to be enclosed in a flat casing.

It is a further object of the invention to provide a midget electron tube having a plug-in base which can be inserted into a socket whose axis may be arranged at any desired angle to the direction in which the axis of the tube is desired to be located.

Other objects of the invention will appear as the description proceeds, reference being had to the accompanying drawing which illustrates by way of example one embodiment of the invention and in which:

Fig. 1 is a perspective view of the tube;

Fig. 2 is an elevational front view of a panel on which three electron tubes are mounted; and

Fig. 3 is a horizontal view to Fig. 2.

In Figs. 2 and 3, three midget electron tubes, generally indicated at 10, 11 and 12, are shown, whose bulbs 13, 14 and 15, respectively, are of flat shape. While in some cases bulbs of round cross section may be used it will in general be preferable to use the illustrated flat shape in order to require as little space as possible in the direction of the thickness of the instrument for which the tubes are used. This instrument may be, for instance, a hearing aid to be worn on the body of the user and the three tubes 10, 11, 12 shown in Fig. 2 may form part of the amplifier of such a wearable hearing aid. Each tube 10, 11, 12 is provided with a base 16, 17 and 18, respectively, arranged at a distance from the corresponding bulb. These bases 16, 17, 18 are flat discs, their only purpose being to hold contact pins 19 in their proper relationship to each other. The bulb of each tube has no bodily contact with the base thereof and is connected to the base solely by the flexible leading-in wires 20 which are secured to the pins 19 of the base, and a substantial part of the length of these leading-in wires 20 extends freely between the bulb and the base. If desired, all or some of the wires 20 may be provided in a well known manner with a flexible insulating cover in the form of a coating or tubing (not shown) over those wire portions just mentioned extending freely between the bulb and the base. Sockets 21, 22 mounted in a panel 24 are provided to receive the pins 19 of the bases 16, 17, 18 of the tubes 10, 11, 12. With the bulb spaced from the

2

base of the tubes in the manner just described the bulbs may be placed in any desired position with respect to the panel 24 and still be plugged into a socket permanently mounted in said panel.

5 In the example shown, all three tubes 10, 11, 12 are arranged so that the axial plane of each tube comprising the larger dimension of the cross-section of the flat bulb extends in a plane parallel to the panel 24, that is, in a plane which 10 is rectangular to the direction of the axis of each of the bases 16, 17, 18. While the bulbs are all shown to extend in the horizontal direction, each of these bulbs could extend under any desired angle to the horizontal direction or, 15 as shown in Fig. 2 for the tube 11, the bulb of any tube may be so arranged that its axis is some distance above or below the center of the corresponding base. Thereby the best possible use of the available space can be made in each 20 particular case. It will further be seen that each tube 10, 11, or 12 may be easily exchanged without unsoldering the leading-in wires of the old tube and soldering on the leading-in wires of the new tube as has been necessary heretofore with midget tubes for wearable hearing aids and similar small instruments, these tubes having been used without a base.

The invention is not limited to tubes having any particular number of electrodes. The tubes 30 may comprise no grid at all, or one or more grids and in the example shown they are assumed to be of the pentode type.

I desire it to be understood that while I have shown in the drawing a certain embodiment of 35 the invention, this embodiment has been given by way of example only and that various changes and modifications may be made without departing from the spirit of the invention or the scope of the appended claims:

40 What I claim is:

1. A midget electron tube comprising a bulb, leading-in wires extending from the outside into said bulb, and a base to be plugged into a socket, said base being spaced from said bulb and connected with the latter solely by means of a flexible connection provided by a portion of said leading-in wires, that end portion of each of said leading-in wires which is next to said base plate being bent substantially perpendicularly to 45 the remainder of the wire and extending at a substantially right angle to the longitudinal axis of said bulb.

2. A midget electron tube comprising a bulb, leading-in wires extending from the outside into 50 said bulb, and a base in the form of a plate car-

rying contact pins projecting perpendicularly therefrom to be plugged into a socket, said plate being spaced from said bulb and being connected with the latter solely by means of a flexible connection provided by a portion of said leading-in wires, that end portion of each of said leading-in wires which is next to said base plate being bent substantially perpendicularly to the remainder of the wire and extending at a substantially right angle to the longitudinal axis 10 of said bulb and to the plane of said plate, into said contact pins.

3. A midget electron tube comprising a flat bulb, leading-in wires extending from the outside into said bulb, and a base in the form of a 15 plate carrying contact pins projecting perpendicularly therefrom to be plugged into a socket, said plate being spaced from said bulb and being connected with the latter solely by means of a flexible connection provided by a portion of 20 said leading-in wires, that end portion of each of said leading-in wires which is next to said base plate being bent substantially perpendicu-

larly to the remainder of the wire, said bent-up end portions being substantially perpendicular to that axial plane of symmetry of the flat bulb which comprises the long axis of the cross-sections of said flat bulb and to the plane of said plate and extending into said contact pins.
